Application October 29, 1938, Serial No. 237,626

12 Claims.

(Cl. 68—58)

This invention relates to laundry apparatus of the type used in power laundries and more particularly to washing machines.

The usual washing machine generally comprises a rotating perforated cylinder or wash wheel enclosed within a stationary shell or tub, the shell being provided with a suitable liquid inlet and also with a drain or dump valve whereby the shell can be alternately filled to a desired liquid level and completely and rapidly emptied. When hot water is required, the water may be heated before being delivered to the inlet, or steam may be admitted to the shell either with the water or separately. Soap, alkali and other supplies may be added to the water before it enters the shell or may be merely thrown into the shell through the usual loading door. With machines of this type, each laundering cycle comprises a routine series of separate operations which may vary in different laundries and with different goods to be laundered; a typical cycle may comprise several sudsing, a bleaching and several rinsing operations, followed in most cases by a souring and blueing operation.

It has been attempted in the past to lower the cost of construction of washing machines and improve their mode of operation by eliminating the shell or tub, the laundering operations being carried on in a single rotatable imperforate cylinder in which the articles to be washed are placed, the said cylinder being mounted rotatably on hollow trunnions through which the several liquids and supplies may be admitted and drawn away as desired.

It has also been heretofore attempted to carry out the washing cycle by various systems of continuous or semi-continuous operation in which water was allowed to flow continuously through the wash wheel during all or certain of the stages of the cycle, while the liquid was maintained at a predetermined level or levels and washing agents were admitted as desired. In the use of such a system the dump valve remains closed until the end of the cycle when washing, rinsing, blueing, etc. are completely finished. Continuous washing has been found to effect a measure of saving of time, heat, water and supplies.

In spite of the desirability of the shell-less washer from the economy viewpoint, little headway has been made in introducing such machines, and prior to the present invention no system of continuous washing has been of a sufficiently practical nature to result in its accept-

ance by laundrymen in place of the usual discontinuous methods hereinbefore mentioned.

One of the objects of the present invention is to provide a practical, efficient and rugged shell-less washing machine. Another object is to provide practical means whereby a machine of this type can be operated efficiently throughout a desired cycle or part thereof in a continuous or semi-continuous manner. Further objects are in part obvious and in part will be pointed out hereinafter.

The invention accordingly consists in the features of construction, combinations of elements, and arrangement of parts as will be hereinafter described, and the scope of the application of which will be indicated in the following claims.

In the accompanying drawings, in which are shown one or more of the various possible embodiments of this invention,

Fig. 1 is in part a front elevation and in part a cross-section through a washing machine in which features of the present invention are embodied;

Fig. 2 is an end view of the machine as viewed from the left in Fig. 1;

Fig. 3 is a right end view;

Fig. 4 is an enlarged cross-section taken substantially on line 4—4 of Fig. 1;

Fig. 5 shows in further enlargement details of the water seal construction and is taken on section-line 5—5 of Fig. 4;

Fig. 6 is a similar cross-section taken on line 6—6 of Fig. 4 showing means for preventing steam or other vapors from escaping from the machine;

Fig. 7 is an enlarged section through the float chamber and associated mechanism taken substantially on line 7—7 of Fig. 1;

Fig. 8 is a section in still further enlargement taken substantially on line 8—8 of Fig. 7;

Fig. 9 is a similar cross-section taken on line 9—9 of Fig. 7; and

Fig. 10 is a cross-section taken on line 10—10 of Fig. 1 looking toward the central partition which divides the interior of the wash wheel into two washing chambers.

Similar reference characters refer to similar parts throughout the several views of the drawings.

Referring to Fig. 1, the present novel washing machine will be seen to have a foundation or frame member 10 comprising at opposite ends upright pedestal members 11 and 12 in which are mounted roller bearing assemblies 13, 14 which respectively rotatably support the trunnions 15

and 16 of the wash wheel 17. Frame member 18 in the present embodiment is supported upon a pair of spaced I-beams 18, 19, themselves supported upon any suitable concrete or other foundation work 20, 21. The space 22 between the foundation members serves as a trough or sewer to receive and carry away waste wash water or other liquids from the wash wheel.

The wash wheel is imperforate throughout its length as regards its circumferential surface, and comprises a cylindrically formed through sheet 25 which extends from a spider member 23 at the left end to a spider member 24 at the right end. Each of these spider members is secured to and hermetically sealed with respect to the interior of the cylinder 25 in any suitable manner, as by welding or riveting. At its center, there is fastened to each of these spiders the corresponding trunnion member 15 or 16. Covering the interior of the left end spider 23 and secured thereto is an imperforate sheet which forms a head 26, and spaced therefrom an appropriate distance and securely fastened to the cylinder 25 is a second imperforate plate or head 27. At the right end of the cylinder, secured to the inner side of the spider 24 in a similar manner, is a perforate plate 28 which serves to discharge water from the wash wheel, as will be herein-after more fully described.

Extending through the left end trunnion 15 is a fluid inlet pipe 29, closed at its inner end and having its lower surface cut away to facilitate the discharge of incoming wash water or supplies downwardly into the inlet chamber 30, between the heads 26 and 27.

Tumbling ribs 31 extend from end to end of the wash wheel and are of usual form and construction. At the left end each of these tumbling ribs passes through the inner head or partition 27 and extends to and terminates in abutment with the outer head 26 to which it is joined, as by means of the angle iron 32. A similar angle iron 33 secures each tumbling rib to the partition 27 and serves to prevent escape of liquids from the inlet chamber 30 to the interior of the wash wheel except through the tumbling ribs themselves. As shown in the present drawings, three of these tumbling ribs are provided, each in alignment with the corresponding arms of the opposing spiders 23 and 24.

The head sheet 28 at the right end of the wash wheel is perforate throughout, except where it covers the tumbling ribs. Consequently no water can flow directly through the tumbling ribs to the discharge chamber at the right end of the machine.

Each tumbling rib is provided at its left end with a plurality of large openings 34 through which liquids in the chamber 30 may rapidly enter the ribs. Each tumbling rib is further provided with a large number of smaller perforations through which the liquids entering the tumbling ribs may be rapidly discharged into the treatment space within the wash wheel. It will be noted that these perforations, indicated by the number 35, vary in their spacing so that there are fewer of them within a given length of the tumbling rib at its left end than at its right. The reason for this arrangement of perforations is that, as will be more fully explained herein-after, according to the preferred operation of the wash wheel it is highly important that liquids should enter the treatment space at an unusually rapid rate and in a manner to insure uniform distribution thereof throughout the wash-

ing chamber. It will be obvious that should water or other liquid be admitted with a rush to the filling chamber 36, if the holes are equally distributed throughout the tumbling ribs, the discharge into the left end of the washing chamber would be much more rapid than at the right end.

A partition 36 which divides the wash wheel into two washing chambers is perforate throughout and does not intersect the tumbling ribs. Thus, whether a machine is constructed to provide one or more washing chambers, uniform distribution of water or supplies will be attained throughout.

Referring to Figs. 1 and 2, it will be seen that secured to the spider 23 at the left end of the machine there is provided a large spur gear 37 with which meshes the pinion 38 of a chain drive leading to the electric motor 39. This motor, as is usual in washing machines, is controlled in its operation so as to drive first in one direction and then in the opposite direction. This is accomplished automatically by means of a well known type of controller, not shown herein.

We have seen that the liquids which include hot and cold water, steam, and the various laundering agents required in carrying out the washing process, are all admitted to the inlet chamber 30 and through the tumbling ribs to the interior of the treatment chamber, by means of the pipe 29 passing through the hollow trunnion 15. The pipe connections to this inlet pipe will be followed and described hereinafter.

Waste wash liquids, as mentioned above, are discharged from the wash wheel through the perforate plate 28 at the right-hand end of the machine, and a discharge space to receive such liquids is formed within a surrounding stationary head member 40 comprising part of the foundation castings. This member 40 envelops the periphery of the wash wheel at its right end. Liquid from the wash wheel flows through the perforate plate 28 into the space 41 between said plate and the rigid head 40, and is prevented from leaking out of the chamber 41 by means of a rubber or other suitable sealing strip 42 making resilient contact with an extended portion of the perforate plate 28. This construction will be more clearly understood by reference to Fig. 5. The rubber strip 42 is supported by a bracket 43 carried by an adjustable slide 44. This slide extends about the lower part of the wash wheel to the points indicated at 45 in Fig. 4 and thus seals the end of the wash wheel to points well above the liquid level maintained within said wheel during operation of the machine. The slide 44 and the foundation casting both are slotted, as at 46, to receive a bolt 46', by means of which the slide may be held in any desired position relative to the foundation member, and adjustment of the slide is by means of adjustment bolts 47 which pass through opposing openings in the opposite ears 48 and 49 respectively of the slide 44 and the foundation casting. By means of this adjustment the rubber sealing strip 42 may be brought to bear upon the extended sheet 28 with any desired degree of pressure. The rubber strip 42 is secured between suitable washers 50 and is held in place by a plurality of bolts 51 passing through the rubber strip, the washers, a flange of the slide 44, and a metal washer 52 provided more securely to hold these various members in proper relationship.

Since steam and hot water are generally used

in the machine, escape of vapors filling the upper portion of the wash wheel should preferably be prevented. For this reason a wiper 53 made of canvas or other suitable material is secured to the interior of the rigid head 40 as by means of an angle iron 54, a pressure strip 55, and a plurality of bolts 56, as will be clearly understood by reference to Figs. 1, 4 and 6.

Referring again to Fig. 1, it will be seen that the stationary head 40 has a large opening provided in its lower part centrally with respect to the vertical axis of the wash wheel. This opening admits waste liquids to a projecting boxlike transition chamber 58 at the bottom of which is located a dump valve 59 of any suitable type. According to the present disclosure (see Fig. 7) the dump valve comprises a valve head 60 in watertight relation to a seat 61 formed upon a spider casting 62 which may be secured to the lower wall of the transition chamber 58 in any desired manner. This spider provides a central guide 63 for the stem 64 of the dump valve, which guide is slotted, as at 65, to permit passage therethrough of the short arm 66 of a dump valve lever which is pivotally supported at 67 by lugs 68 extending downwardly from the spider 62. By reference to Fig. 3 it will be seen that the longer arm 69 of this lever extends beyond the foundation at the front of the machine where it is furnished with a pivoted treadle 70. The dump valve lever has a ball-and-socket connection with the valve stem 64 as indicated at 71 in Fig. 7.

The right-hand wall 72 of the transition or dump chamber 58, as viewed in Figs. 3 and 7, is also provided with a central opening 73 of substantially the same height as the opening 57, but of less width. This opening leads into a float chamber 74 included within a sheet metal housing 75 suitably secured to the right-hand wall of chamber 58. From the lower part of the chamber 74 a pipe 76 descends for a purpose explained hereinafter.

The outer or right-hand wall of the float chamber 74 comprises a guide 77 for a sliding gate or weir 78. Mounted upon this sliding gate is the fulcrum pin 79 of the float lever 80, and also carried by this gate is a bracket 81 between the flanges 82, 83 of which is supported a lever arm 84. This arm 84 is connected at its outer end, as at 85, by a pin with one end 86 of a link, connected at its other end 87 with a short arm 88 of the float lever 80. The lever arm 84 slidably surrounds a squared rod 89 which serves automatically and periodically, and through means hereinafter to be described, to cause sudden and rapid admission of water to the inlet pipe 29.

These features of construction may best be understood by reference to Figs. 3, 7, 8 and 9. Fig. 9 clearly shows the squared rod 89 passing loosely between the flanges of the bracket 81 and carrying the lever arm 84 link-connected to the upper end of float lever 88, the latter being yoke-shaped and supported by the pin 79 in the bracket 81. The gate or adjustable weir 78 slides in the guides of the part 77 as is more clearly shown in Figs. 7 and 8, and is held against the surface of the guide plate 77 by means of spring-pressed plungers 90 mounted in sockets 91 formed on the gate member, the outer ends of the plungers slidably engaging a plate 92 bolted to and spaced away from the guide plate 77.

It will be understood that the gate or weir 78

serves to determine the minimum level at which water or other liquids may overflow and drain away from the float chamber and consequently from the wash wheel. The float 93 mounted upon the lever 80 serves to control the opening of the admission valve to suddenly admit relatively large amounts of water to the interior of the wash wheel when a certain minimum level obtains in the float chamber. This level, however, is variable, for at certain periods during the laundering operation it is desirable to operate at approximately a 5" level in the wash wheel, while during other operations in the cycle an 8" or 9" level may be desirable.

This changing of level is obtained by operating a hand lever 94 at the front of the machine which, through a link 95 and a bell crank lever 96, raises or lowers a rod 97 rigidly secured to the sliding gate. The gate and float construction thus provides that any adjustment of the sliding gate to permit the outflow of water at a raised or lowered level correspondingly raises the fulcrum of the float 93 so that the float 93 always operates within a narrow zone of maximum and minimum levels in predetermined relation to the position of the upper edge of the sliding gate.

This raising or lowering of the gate does not alter the relationship of the connections between the float lever and the lever arm 84 to the squared rod 89, since the lever arm 84 is freely slideable up and down the rod 89. As will be noted by reference to Fig. 7, the rod 89 is pivotally supported at its lower end as at 98, within a bracket 99 secured to the gate retaining plate 92. All of this float lever and gate mechanism is contained within an ultimate discharge chamber within a casing 100 secured to the right-hand wall of the float chamber 74 and provided with openings in its upper wall for the passage of the rods 97 and 89.

Referring to Figs. 1, 2, 3 and 4, the pipe connections for leading water and supplies to the wash wheel, for leading waste liquid away from the ultimate discharge chamber, and for recirculating liquid between the float chamber and the inlet may now be described.

A pipe 101 leads hot water to a fitting 102 connected by a nipple 103 with a mixing valve 104. A similar pipe 105 leads cold water to a fitting 106 connected by means of a nipple 107 with the same mixing valve 104. This mixing valve is of a well known type and need not be described, it being sufficient to say that it may be adjusted to mix hot and cold water and deliver from its outlet water of any desired temperature. Its outlet is shown in Fig. 3 at 108 and this is connected by means of a pipe 109 to the inlet side of a piston operated valve 110, the outlet 111 of which is connected to a pipe 112 connected to the inlet pipe 29, above mentioned, by means of a side outlet T 113. To accomplish recirculation of liquid from the float chamber through the washer the side outlet of the T 113 is connected to the inlet pipe 29 while the bottom opening is connected by means of a pipe 114 to the pipe 76 mentioned above as being connected with the float chamber. The connection between the pipes 76 and 114 is an injector fitting 115 which also connects with a steam line 116. This injector forces water from the float chamber into the washer through the inlet pipe 29. A hand-controlled valve 117 serves to control steam to the injector, and a check valve 118 serves to prevent fluid from passing from the water inlet pipe

112 to the recirculation pipe 114, but permits the passage of fluid in the opposite direction.

Surmounting the piston-operated valve 110 is a fluid pressure chamber containing a piston, indicated at 119 in Fig. 2. This valve is normally held closed against the pressure in supply pipe 109 by means of fluid pressure exerted upon the upper side of piston 119.

Liquids are normally drawn off from the overflow or ultimate discharge chamber by means of a pipe 120, best shown in Fig. 3, which connects with a channel 121 formed in the wall of said chamber. In this pipe 120 is located a valve 122 which may be adjusted by hand to control the flow of water from the said chamber at any desired rate. The float 93 is so adjusted that there will always be a flow of water over the top of gate 18; that is, the minimum level at which the float acts to admit water to the inlet of the wash wheel is maintained slightly above the top of the sliding gate in any one of its adjusted positions. This arrangement results from the discovery that in all stages of the cycle of washing, best results are attained with a controlled continuous discharge and an intermittent rapid admission of water or washing fluids from and to the wash wheel.

For this reason 3" pipe is used for the water supply to the wash wheel so that when the piston valve 110 opens—and opens fully as it does in accordance with the present invention—a large volume of water instantly rushes into the inlet chamber 30 of the wash wheel, thence through the tumbling ribs into the treating chamber of the wash wheel where the materials being washed are disposed. The advantages derived from such action will be more fully brought out hereinafter.

The piston chamber of the valve 110 is connected above the piston 119 in a 3/4" pipe line comprising a pipe 123 connecting with the water supply pipe 109, as by means of a fitting 124. In pipe 123 is arranged a restriction valve 125 of well known type which may be adjusted to restrict the passage of water from the supply pipe 109 to the piston valve 110 and thus control the fluid pressure exerted upon the piston 119. The piston chamber is also connected by means of a pipe 126 with a pipe 127 discharging freely into the dump valve chamber 58. In this pipe 126 is located a pilot valve 128 operated by means of a bell crank lever 129 and a link 130 connecting the bell crank lever 129 with a lever arm 131 fixed upon the beforementioned squared rod 89. The arrangement and adjustment of the mechanical and fluid connections to valve 128 is such that after a predetermined, downward movement of the float 93, continued downward movement will cause sufficient opening of valve 128 to release the fluid pressure from the upper side of the piston valve, permitting an immediate full opening of said valve and a consequent rapid flow of water into the wash wheel. It will be understood that with the admission of water to the wash wheel the valve 128 will be gradually moved by the float toward its closed position but will not reach that position to effect closure of the piston valve until the float has reached its high level.

A second valve 132 (normally open) is connected in pipe line 126 and this valve is connected by means of lever 133 and link 134 to the dump valve lever 89, as indicated at 135. The arrangement is such that when the dump valve is closed, as normally it is, valve 132 is open so that piston operated valve 110 may be opened by the release

of pressure in the 3/4" pipe line through the opening of valve 128. However, when the dump valve is open and the water or fluids in the wash wheel are being rapidly discharged therefrom, the lowering of the water level in the float chamber and consequent opening of valve 128 will not be effective to release the pressure from the piston operated valve and thus cause the opening of the supply pipe to the interior of the washer.

Supplies such as soap, soda, bleach, blueing, etc., are admitted by running the desired quantity into the hopper 136, best shown in Fig. 2. This is connected to a water supply line 137 containing a hand-controlled valve 138 and a check valve 139. When supply or recirculation water is not flowing to the inlet pipe 29, a load of any washing agent contained in hopper 136 may be flushed into the inlet chamber 30 of the wash wheel by opening valve 138, valve 139 preventing a flow of water into the hopper from any other connection to the T fitting 113. It is particularly in respect to this admission of supplies that uniform distribution by means of the tumbling ribs is valuable, since certain of these supplies coming in contact with the clothes in an undiluted state have deleterious effects and produce non-uniform washing results.

It will thus be understood that the washing agents are admitted into the inlet chamber 30 of the wash wheel during intervals when water is not flowing thereto from another source. These supplies, with the water which flushes them into the inlet chamber, are thoroughly mixed in that chamber so that when water is next flooded into the chamber from the supply pipe at the rapid rate upon which the operation of this machine is predicated, the washing agents are almost instantly carried by this great influx of water through the tumbling ribs to all parts of the treating chamber and uniformly distributed throughout said chamber.

Referring to Figs. 1 and 4, there will be seen in the discharge space within the rigid head 48, attached to the wash wheel, in alignment with each of the tumbling ribs 31, three paddles 140. The exact location of these paddles is not important nor their number, and in fact under certain conditions of operation they may be omitted entirely. However, it has been found that they render more certain the operation of the float lever valve arrangement when the water level lowers to its predetermined minimum.

While it is entirely feasible to operate the shell-less washer above described in the usual manner admitting the supplies and carrying out each operation of the cycle independently and opening the dump valve to release each charge of water after it has performed its function, it has been found that great economy results when the machine is run as suggested above, with a constant discharge of liquid at a predetermined rate and an intermittent and controlled admission of supply water in large quantities at a very rapid rate. This inrush of water not only aids in distributing the laundering agents, but further, results in a better and more satisfactory cleansing of the materials within the container.

As mentioned in the beginning of this specification, the idea of flowing water continuously through a washing machine is not new, but in such arrangements, difficulties have been experienced in securing uniform distribution of supplies and such operation has resulted in less economy of water, fuel, labor and supplies than results from the intermittent operation of the

present invention. This will be understood since, in continuous flow arrangements, the inlet valve is only slightly opened at any one time, or perhaps it might be said to be in a floating condition, water entering and leaving the machine continuously at a very slow rate. The effect of this is that the change, we will say from sudsing to a clear condition during a particular rinse, is slow and the emulsified washing agents and soil are not readily removed from the clothes. But when operating as described herein, that is with periodic sudden inrushes of water to the treating chamber, there is active agitation of the clothes by means of the rushing water and a thorough removal of the particles of soil and laundering agents. As compared with the ordinary methods it has been found that for an exactly corresponding washing cycle a great saving is made in operating according to the present process, in water, laundering supplies, time, labor and fuel.

In Fig. 7 two spaced broken lines indicated respectively by the words "low" and "high" show the range of liquid levels in the float chamber during the operation of the machine. At the beginning of a washing operation such as sudsing, the water may be considered as standing at the high point and flowing over the weir or gate 78 and into the sewer by means of the pipe 126 at a rate predetermined by the adjustment of the valve 122. The level in the wash wheel and in the float chamber will therefore fall until the low point is reached when the float will act quickly to open the pilot valve 128 effecting a release of the fluid pressure above the piston of the valve 110. Under these conditions valve 110 will immediately open fully and water will rush into the inlet chamber 38 of the wash wheel immediately passing through the tumbling ribs into the treating chamber of the wheel. The water inlet valve will continue open until the level rises to the predetermined high point when a rapid shutting of the pilot valve will take place causing an immediate closing of the piston valve and thus cutting off the water supply to the wash wheel. Such operation is believed to be novel, for the present inventors who have had long experience in the laundering field are unaware of any continuous washing operation wherein waste liquids are discharged at a given rate and supply water admitted rapidly and periodically in large quantities.

The mere falling of the water level will effect the opening of the pilot valve and consequent operation of the piston valve, but it has been found that the action of the float is more certain when the paddles 140 are used since these paddles effect in the discharge chamber a condition of turbulence similar to that which is taking place simultaneously in the wash wheel itself. As the wash wheel rotates it will be understood that the tumbling ribs lift not only clothes but quantities of water which is constantly falling back into the bottom of the wheel. Thus the mean level in the wash wheel is constantly changing, and particularly is this true upon each reversal of the driving motor. Since, therefore, the hydraulic head within the washer is continually changing, it is desirable to have the hydraulic head in the discharge chamber vary correspondingly.

It will be noted that each of the tumbling ribs extends across the fluid inlet space 30 so that the included portion of each rib serves to produce a condition of turbulence in the inlet cham-

ber corresponding to the turbulent condition existing in the wash wheel. This aids greatly in mixing incoming laundering agents with the water standing in the inlet chamber prior to its passage through the tumbling ribs into the wash wheel itself. Too much stress cannot be put upon the importance of this thorough mixing of laundry supplies with an adequate quantity of water before they are permitted to come in contact with the materials within the container since it is a well known fact that too great a concentration of a supply such as that used as a bleach may seriously affect the texture of certain types of materials and, in the case of bleaching, an uneven distribution produces streaky effects in the finished goods.

Referring again to Figs. 4 and 5, it will be seen that the slide 44 is provided, as at 44', with a sector of an annular flange which extends the full circular length of the slide. Through this flange at its lowest point is provided a drain opening 44". Thus a trough is formed between the bracket 43 and the flange 44' adapted to catch any liquid from the wash wheel which may seep past or splash over the ends of the sealing strip 42. The drain 44" enables such seepage to drain off into the sewer 22.

It will thus be seen that there has been provided by this invention an apparatus in which the various objects hereinabove set forth, together with many thoroughly practical advantages, are successfully achieved.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

We claim:

1. In a washing machine, in combination, an imperforate rotatably mounted wash wheel, a discharge chamber having means for continuously discharging liquid therefrom at a substantially constant rate, a transition chamber communicating with said wash wheel at all operable liquid levels, means comprising an intermediate chamber providing continuous communication between said transition chamber and said discharge chamber at a predetermined liquid level, alternatively fully open and shut cut-off means for admitting liquid to said wash wheel when open at a rate greater than said discharge rate, and actuating means associated with said intermediate chamber adapted intermittently to open and close said liquid admission means, said actuating means being operatively responsive to minimum and maximum level variations relative to said predetermined liquid level.

2. In a washing machine, in combination, an imperforate rotatably mounted wash wheel, a discharge chamber having means for continuously discharging liquid therefrom at a substantially constant rate, a transition chamber communicating with said wash wheel at all operable liquid levels, means comprising an intermediate chamber providing continuous communication between said transition chamber and said discharge chamber at a predetermined liquid level, alternatively fully open and shut cut-off means for admitting liquid to said wash wheel when open at a rate greater than said discharge rate, and actuating means associated with said intermediate chamber adapted to open said admission means in response to a fall in level to a pre-

terminated point relative to said liquid level and to close said admission means in response to a rise in level to another predetermined point relative to said liquid level, both of said points being above said liquid level.

3. In apparatus of the character described, in combination, a rotatably mounted imperforate cylinder having means for admitting liquids to and means for discharging liquids from said cylinder while it is in operation, at least one of said means comprising a stationary receptacle formed within a stationary head enclosing an end of said cylinder, means providing communication between the interior of said cylinder and said receptacle, means for maintaining a liquid level within said cylinder and receptacle substantially above the bottom of said cylinder, and means for establishing a substantially liquid-tight seal between the exterior of said cylinder and the interior of said stationary head.

4. In apparatus of the character described, in combination, a rotatably mounted imperforate cylinder having an end open to the passage of a liquid, a stationary head having formed therein a stationary liquid receptacle communicating with the interior of said cylinder and comprising a rim surrounding at least a portion of the periphery of said cylinder adjacent said end, means for maintaining a liquid level within said cylinder and receptacle substantially above the bottom of said cylinder, and means on said cylinder and said stationary head for establishing a liquid-tight seal between the exterior of said cylinder and said receptacle.

5. In apparatus of the character described, in combination, an imperforate wash wheel rotatably supported by trunnions carried by head structures at its opposite ends, a partition suitably spaced from one end to provide a receiving chamber between said partition and said one end, and a wash chamber between said partition and the other end of the wash wheel, means for admitting liquids to said receiving chamber and means for discharging liquids from said wash chamber during rotation of said wash wheel, a plurality of conduits each communicating with said receiving chamber and with the wash chamber throughout the length thereof, the aggregate flow area of the means of communication between said conduits and said wash chamber per unit length of said conduits being progressively greater from the inlet to the remote end of said conduits.

6. In apparatus of the character described, in combination, an imperforate wash wheel rotatably supported by trunnions carried by head structures at its opposite ends, a plurality of partitions suitably spaced to provide a receiving chamber adjacent one end and a plurality of wash chambers between said receiving chamber and the other end, means for admitting liquid to said receiving chamber during rotation of said wash wheel, means for maintaining a predetermined liquid level within said cylinder, a plurality of continuous hollow tumbling ribs extending into all of said chambers adjacent the periphery of the wash wheel and having openings therein constituting the sole means of communication between said chambers, said openings being disposed according to a predetermined pattern based upon the relative position of said receiving chamber to the respective wash chambers for effecting equal distribution of liquids from submerged tumbling rib areas to all of said wash chambers.

7. In apparatus of the character described, in combination, an imperforate wash wheel rotatably supported by trunnions carried by head structures at its opposite ends, a partition suitably spaced from one end to provide a receiving chamber between said partition and said one end, and a wash chamber between said partition and the other end of the wash wheel, means for admitting liquids to said receiving chamber and means for discharging liquids from said wash chamber during rotation of said wash wheel, a plurality of tumbling ribs secured to the periphery of said wash wheel and to both of said head structures and passing through said partition to serve as the sole means of communication between said receiving and wash chambers, and means providing communication between each of said chambers and the portions of said tumbling ribs included therein, the means of communication with said wash chamber comprising perforations distributed throughout the length of the corresponding portions of said ribs, the aggregate area of said perforations per unit length of said ribs being progressively greater from the inlet to the remote ends of said ribs.

8. In apparatus of the character described, in combination, a rotatably mounted imperforate cylinder adapted to discharge liquid freely through a perforate end thereof into a liquid receptacle contained within an enclosing stationary head which surrounds and is in liquid-tight relationship to the periphery of said cylinder at said end, means for controlling the liquid level within said cylinder comprising a float adapted to rise and fall in accordance with liquid level changes within a float chamber, means providing free communication between said liquid receptacle within said head and said float chamber, a cut-off valve connecting the interior of said cylinder with a water supply, and means responsive to the rise and fall of said float for controlling the operation of said valve.

9. In apparatus of the character described, in combination, a rotatably mounted imperforate cylinder adapted to discharge liquid freely through a perforate end thereof into a liquid receptacle contained within an enclosing stationary head which surrounds and is in liquid-tight relationship to the periphery of said cylinder at said end, periodically reversible driving means for said cylinder, means for controlling the liquid level within said cylinder comprising a float adapted to rise and fall in accordance with liquid level changes within a float chamber, means providing free communication between said liquid receptacle within said head and said float chamber, a cut-off valve connecting the interior of said cylinder with a water supply, means responsive to the rise and fall of said float for controlling the operation of said valve, means in said cylinder adapted at each reversal of said driving means to effect substantial changes in the liquid level within said cylinder, and means mounted upon said cylinder within said liquid receptacle for effecting corresponding substantial changes of liquid level within said float chamber.

10. In apparatus of the character described, in combination, a rotatably mounted imperforate cylinder adapted to discharge liquid freely through a perforate end thereof into a liquid receptacle contained within an enclosing stationary head which surrounds and is in liquid-tight relationship to the periphery of said cylinder at said end, means for controlling the liquid level within a float chamber comprising a gate adjust-

able to provide an outlet from said chamber at different predetermined levels and a float pivotally mounted on said gate, means providing free communication between said liquid receptacle within said head and said float chamber, a cut-off valve connecting the interior of said cylinder with a water supply, and means responsive to the rise and fall of said float for controlling the operation of said valve.

11. In apparatus of the character described, in combination, an imperforate wash wheel rotatably supported by trunnions carried by head structures at its opposite ends, a partition suitably spaced from one end to provide a receiving chamber between said partition and said one end and a wash chamber between said partition and the other end of the wash wheel, means for admitting liquid to said receiving chamber and means for discharging liquid from said wash chamber during rotation of said wash wheel, means for causing agitation of liquid in each of said chambers comprising included portions of a plurality of hollow tumbling ribs extending between and secured to said head structures and to the periphery of said wash wheel interiorly there- 25

of and passing through said partition in a liquid-tight manner, and means providing communication between each of said chambers and the portions of said tumbling ribs included therein.

5 12. In apparatus of the character described, in combination, a rotatably mounted cylindrical wash wheel providing therein a wash chamber formed between two transverse walls and surrounded by an imperforate wall of the wash wheel, means for admitting liquid to and means for discharging liquids from said chamber while said wash wheel is in motion, at least one of said means comprising a stationary receptacle formed within a stationary housing surrounding a portion of said wash wheel adjacent one of said transverse walls and in communication with said wash chamber through perforations in said one wall, means for maintaining a liquid level within said cylinder and receptacle substantially above the bottom of said cylinder, and means for establishing a substantially liquid-tight seal between the interior of said wash wheel and the receptacle within said housing.
